(57) **CLAIM**

The ornamental design for a mobile phone with animated graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

1. Mobile phone with animated graphical user interface

1.1 is a front view of a mobile phone with animated graphical user interface;

1.2 is a rear view thereof;

1.3 is a left view thereof;

1.4 is a right view thereof;

1.5 is a top view thereof;

1.6 is a bottom view thereof;

1.7 is a front view showing the second image in the sequence, where all other views remain the same as those shown in FIGS. 1.2-1.6;

1.8 is a front view of the third image thereof; and,

1.9 is a front view of the screen as it appears in the last image of the transition shown flattened end separated from the mobile phone for clarity of illustration only.

The appearance of the transitional image sequentially transitions between the images shown in reproductions 1.1, 1.7 and 1.8, where the 1.2-1.6 back, side, top and bottom views

(Continued)

remain static. The process or period in which one image transitions to another image forms no part of the claimed design.

The broken lines showing portions of the mobile phone form no part of the claimed design.

1 Claim, 9 Drawing Sheets
